UNITED STATES PATENT OFFICE.

HENRY TAYLOR, OF CHICAGO, ILLINOIS.

CHAIN-LINKS.

1,091,255.

Specification of Letters Patent. Patented Mar. 24, 1914.

Application filed November 20, 1913. Serial No. 802,110.

To all whom it may concern:

Be it known that I, HENRY TAYLOR, a citizen of the United States, residing at Chicago, in the county of Cook and State of Illinois, have invented certain new and useful Improvements in Chain-Links; and I do declare the following to be a full, clear, and exact description of the invention, such as will enable others skilled in the art to which

10 it appertains to make and use the same.

This invention relates to ornamental chains for supporting electric chandeliers or drop lights and the object of the invention is to partially conceal the current conducting wires leading from the conduit in the ceiling to the lights.

With the above object in view, the invention resides in the structure described and claimed and shown in the drawings where-
20 in:

Figure 1 is a side elevation of a portion of a chain constructed in accordance with my invention and showing the current conducting wires in position, Fig. 2 is a vertical section through a plurality of the links taken on the line 2—2 of Fig. 1, and Fig. 3 is a horizontal section taken on the line 3—3 of Fig. 1.

In the accompanying drawings, I have shown a plurality of links 1 which may be of any size and configuration and may be either solid or split at suitable points.

Each link 1 is provided with a peripheral groove 2 and with aligned openings 3 extending through the upper and lower ends of said link and communicating with said groove. By reference to Fig. 2 of the drawings, it will be seen that when the links 1 are assembled, the aligned openings 3 in the adjoining links will register.

The current conducting wires 4 leading

from the conduit within the ceiling are passed through a ring 5, bent outwardly and seated within the groove 2 of the uppermost link 1, and are passed upwardly through the lower opening 3 in the upper link, through the upper opening 3 in the next link, and are then bent downwardly into the groove 2 of this link. This operation is repeated successively until the end of the chain is reached and at this point the wires 4 are connected in the usual way to the sockets of the electric bulbs.

I may construct my improved chain of brass, copper, iron, or other suitable material so finished as to present a neat appearance, and although I have shown the links of the chain as elliptical, it will be clear that they may be circular or right angular.

Having thus described my invention, what I claim is:

1. A link having a peripheral channel and openings through the body of said link communicating with said channel.

2. A split link having a peripheral channel and aligned openings through the body of said link communicating with said channel.

3. The combination with two wires, of a chain composed of a plurality of peripherally grooved links, said links being provided with registering openings in communication with the grooves in said links, and said wires being arranged within the grooves of the links and passed through the registering openings in the adjoining links.

In testimony whereof I have hereunto set my hand in presence of two subscribing witnesses.

HENRY TAYLOR.
